UNITED STATES PATENT OFFICE

123,019

DESIGN FOR A COFFEE BREWER STAND

Mark W. Rivers, Los Angeles, Calif.

Application May 18, 1940, Serial No. 92,447

Term of patent 3½ years

To all whom it may concern:

Be it known that I, Mark W. Rivers, a citizen of the United States, residing at Los Angeles, in the county of Los Angeles, State of California, have invented a new, original, and ornamental Design for a Coffee Brewer Stand, of which the following is a specification, reference being had to the accompanying drawing, forming a part thereof.

Fig. 1 is a perspective view of the coffee brewer stand, showing my new design;

Fig. 2 is a top plan view thereof; and

Fig. 3 is a side elevational view thereof.

I claim:

The ornamental design for a coffee brewer stand, as shown.

MARK W. RIVERS.
